CLAIM

The ornamental design for a leg for camping cot as shown and described.

DESCRIPTION

FIG. 1 is a perspective view of a leg for camping cot showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view shown in an extended configuration.

In FIG. 8, the broken lines depict portions of the leg for camping cot that form no part of the claimed design.
